JAMES L. JACKSON.

UNITED STATES PATENT OFFICE.

JAMES L. JACKSON, OF NEW YORK, N. Y.

DESIGN FOR MANGERS.

Specification forming part of Design No. 5,398, dated December 5, 1871.

To all whom it may concern:

Be it known that I, JAMES L. JACKSON, of the city and State of New York, have invented or produced a Design for a Manger; and the following is declared to be a correct description thereof.

This manger is adapted to stables, and is to be made of cast-iron or other metal.

The design of the shape and configuration is shown in the annexed drawing, wherein Figure 1 is a perspective view of the manger complete, and Fig. 2 is a section vertically.

The manger is of the shape and configuration

represented. The upper portions are marked *a b*. The top plate *e* is made of the form shown sectionally in Fig. 2, to set upon the mangers and against the sides of the stall.

I claim as my invention—

The design of the shape and configuration of the manger, as described and represented, also, the sectional shape of the top plate *e*, as shown.

Signed by me this 13th day of July, A. D. 1871.
JAMES L. JACKSON.
